UNITED STATES PATENT OFFICE.

WERNER SIEBERT, OF CHARLOTTENBURG, GERMANY, ASSIGNOR TO GENERAL ELECTRIC COMPANY, A CORPORATION OF NEW YORK.

DEVICE FOR SYNTHESIZING GAS.

1,061,786.

Specification of Letters Patent. Patented May 13, 1913.

Application filed February 5, 1908. Serial No. 414,318.

To all whom it may concern:

Be it known that I, WERNER SIEBERT, a subject of the King of Prussia, residing at Charlottenburg, Germany, have invented 5 certain new and useful Improvements in Devices for Synthesizing Gases, of which the following is a specification.

This invention relates to the process of bringing about the combination of gases 0 such as atmospheric nitrogen and oxygen and comprises both a method and a device to combine these gases under the most economical conditions of energy consumption.

The technical application of the well-known process of burning the nitrogen by means of an arc of high potential depends 5 for its success upon some procedure or device for spreading out the arc as much as possible. Various means to accomplish this 0 effect have been devised. The blowing-out effect of the electromagnet has been employed to scatter the arc. The arc has been drawn out to a great length and the air currents passed in a spiral whirl about the 5 axial arc. In both of these methods the gases are removed comparatively slowly out of the influence of the arc, thus causing the 0 oxid of nitrogen to decompose in the colder regions of the arc. Not a small part of the electrical energy is thus needlessly lost.

This undesirable effect is avoided in the present invention. By a peculiar motion of the air current the arc is not only spread out as far as possible but the air once acted 5 upon is suddenly and strongly cooled as it leaves the influence of the arc.

The means for accomplishing this purpose may be better understood from the following description taken in connection with 0 the accompanying drawings.

The features of novelty are pointed out in the appended claims.

Figure 1 shows a longitudinal section of my device; Fig. 2 shows a longitudinal section of a slightly modified form of the apparatus.

Inside the drum 1, Fig. 1, which may be made of iron, is placed a smaller concentric iron cylinder 2, electrically insulated 0 from the outer cylinder 1 and closed on all sides. Both cylinders are connected to a source of electric current 3.

A concentric ring of iron 4 of same height

as cylinder 2 may be conveniently placed along the inner wall of the drum, but is not 55 essential. The ring 4 and the cylinder 2 have their upper surfaces substantially in the same plane as indicated in the drawings. A rod 5 extends tangentially from the cylinder 2 toward the outer cylinder 1. The 60 space intervening between the pointed rod 5 and the cylinder 1 is such that a current of a voltage of 5,000 to 10,000 volts can leap across forming an arc.

The annular space intervening between 65 the two concentric cylinders 1 and 2 is from 20 to 100 fold greater than this distance and such that current at the operating voltage cannot jump across.

A fan 6, connected to some suitable source 70 of power 7 below the inner concentric cylinder 2, gives to the air or other suitable mixture of gases entering the drum at an intake pipe 8 a whirling upward motion. The spark or arc forming at the end of the rod 75 5 is blown upward by the air current and is forced to glide along the space intervening between cylinder 2 and the drum 1 as at ring 4. This circular motion is so rapid that the spark or arc takes the form of a 80 flat disk-like discharge and fills the intervening space almost completely. The air currents pass in a screw-like motion through the arc, and the individual air particles remain in the same just long enough so that 85 the theoretically possible amount of oxid is formed. When the air leaves the arc it mixes instantly, because of its velocity, with the air already cooled so that a decomposition of the oxids already formed can no 90 longer occur. The gases leave the drum through an exit pipe 9.

The air encompassed by the arc being heated is a better conductor of the current than the air surrounding the end of the rod 95 5 which is cool. Therefore, a striking back of the arc seldom occurs. It is well, in order to further guard against a possibility of striking back, not to let the operating voltage rise as high as that necessary for starting. This may be easily done by means of a choke coil. The regulation of the speed of the air current will likewise contribute to prevent the arc from striking back.

Other means of communicating a whirling 105 motion to the air in the drum readily sug-

gest themselves. The air may be blown from intake pipe 10 through nozzles 11 in a tangential direction as shown in Fig. 2.

The speed of revolution of the air currents 5 may be conveniently controlled by a valve 12 which will regulate the influx of air in the intake pipe 10. The spiral currents of air pass between the concentric cylinders 13 and 14 in the same way as shown in Fig. 1. The 10 arc is started in the same way from the tangential rod 15.

What I claim as new and desire to secure by Letters Patent of the United States, is,—

1. The process of producing chemical 15 actions in gases which consists in starting an arc between electrodes separated by an annular space, passing the gases while rotating in said space across said arc, thereby forcing said arc to glide along the annular space 20 whereby the electric discharge takes a disk-like form.

2. The process of causing chemical reaction in gases which consists in striking an 25 arc by a high voltage current between cylindrical electrodes separated by an annular space and passing the gases with a whirling motion across the arc, thereby shifting the same to a point at which the separation of 30 said electrodes is greater than the striking distance of the operating voltage, and causing said arc to glide along said annular space where it appears as a disk-like flame.

3. The process which consists in starting 35 an arc between concentric electrodes at a point of least separation by high voltage discharge, passing gases in a whirling motion between said electrodes, thereby transferring the arc to a point of greater separation of

said electrodes and continuing said arc at this point in a plane at right angles to the 4 axis of the electrodes.

4. The combination of coöperating electrodes having their upper surfaces substantially in the same plane, one of said electrodes being situated within the other, 4 means for striking an arc between said electrodes and means for passing air in a spiral path in a general forward direction at right angles to said arc.

5. The combination of a cylindrical electrode, an insulated electrode, situated within the same, the upper surfaces of said electrodes being substantially in the same plane, a source of electric current, means for starting an arc discharge across the space intervening between said electrodes, and means for setting the gases intervening between the concentric electrodes into a progressive whirling motion.

6. The combination of a cylindrical, metallic drum, a shorter metallic cylinder located in the drum and separated therefrom, said drum and cylinder constituting concentric electrodes, a source of current therefor, means for striking an arc between said electrodes, and means for driving with a rotating motion gases to be chemically acted upon through said drum at a rate which will cause the arc to assume a flat, disk-like form.

In witness whereof, I have hereunto set my hand this 18 day of January, 1908.

WERNER SIEBERT.
